Primary Examiner — Marissa J. Cash*Assistant Examiner* — Kayla Marie Bennett(57) CLAIM

The ornamental design for a utility rack, as shown and described.

DESCRIPTION

FIG. 1 is a first perspective view of a utility rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The utility rack comes with 4 slots and 4 hooks and helps to utilize wasted door space by transforming it into compact and efficient tool storage. It can efficiently organize a wide range of cleaning and household items, just hang it over the door with the included hooks without causing any damage.
